FOOTWEAR

James Shapiro, Brookline, Mass.

Application December 16, 1938, Serial No. 246,022

5 Claims. (Cl. 36—45)

This invention pertains to footwear, and relates more particularly to shoes of the pump type. Such shoes are unprovided with retaining means such as laces, buttons or the like, and must have a sufficiently tight fit at the top margin of the upper to hold them firmly on the foot. As pumps are commonly provided with high heels, the foot tends to slip forward and consequently the top edge of the upper, at the throat end of the foot-receiving opening, tends to cut into the flesh of the foot, an effect particularly noticeable when the wearer is at all overweight. This causes great discomfort and sometimes even permanent injury, and although this effect may be somewhat relieved after the pump has been worn for a considerable period, due to the stretching of the upper material at the forward end of the throat opening, any comfort resulting therefrom is obtained at the sacrifice of good fit and good looks. Various expedients have been proposed for remedying the above difficulty, such, for instance, as the application to the edge of the upper of a removable shield, for instance of rubber, Celluloid, metal or the like, designed to provide a round or blunt bearing surface against which the forward part of the foot may press; the use of a piece of leather or other sheet material disposed to embrace the edge of the upper proper at the throat and which is usually stitched or otherwise attached to the upper so as to become a permanent part of the latter and to provide a thickened edge; or the formation of the upper at the forward end of the throat opening so as to be capable of stretching transversely, thereby to simulate the effect of long wear. However this procedure sacrifices looks and good fit in order to obtain the desired comfort, and also complicates the lasting operation, since if a shoe upper be unduly elastic at its upper portion, it is difficult to avoid undersizing the shoe in lasting.

Thus none of the prior expedients fully solves the problem or meets the requirements of the retail trade or of good and economical shoe making, and it is the object of the present invention to provide a pump having the edge of the upper at the throat end of the foot-receiving opening so padded as to afford adequate comfort of the foot but so designed and arranged that it does not detract from the appearance of the shoe or decrease its useful life, and at the same time to permit the shoe to be made economically by usual and practical factory operations.

In attaining this object, the present invention contemplates providing the edge of the upper at the throat end of the foot receiving opening with

a rounded roll-like guard whose outer covering or surface is of the same finish as the adjacent portions of the upper and which preferably constitutes an integral part of the material forming the outer member of the upper at this part 5 of the shoe, said guard roll including a core member which is substantially inextensible so as to assist the upper in resisting transverse stress, the core comprising soft cushion-like padding material. The roll-covering is provided with 10 ventilating openings designed to allow the escape of any moisture which may be absorbed from the foot by the padding material, but these ventilating openings are of such character as not seriously to decrease the normal resistance of 15 the roll-covering material to elongation transversely of the foot.

Other objects and advantages of the invention will be pointed out in the following more detailed description and by reference to the accompanying drawings, wherein

Fig. 1 is a side elevation, to small scale, of a pump embodying the invention;

Fig. 2 is a fragmentary plan view, to somewhat larger scale, showing the throat portion of the 25 upper and the forward end of the foot-receiving opening;

Fig. 3 is a fragmentary plan view of the forepart of the upper, to still larger scale, showing the throat end of the foot-receiving opening and 30 the improved guard-roll of the present invention associated therewith;

Fig. 4 is a fragmentary section, to greatly enlarged scale, on the line 4—4 of Fig. 3;

Fig. 5 is a fragmentary perspective view showing one desirable form of core member for the 35 roll;

Fig. 6 is a plan view, to smaller scale, showing the vamp-piece, usually of leather or the like, prepared for use in making the improved pump 40 of the present invention;

Fig. 7 is a plan view of a leather lining member;

Fig. 8 is a plan view of a fabric lining member;

Fig. 9 is a plan view of a doubler piece; 45
Fig. 10 is a fragmentary plan view of the inner side of the vamp at the forepart, before assembly with the lining members, and showing the pad disposed in readiness to be enfolded within the perforated vamp material to form the 50 guard roll;

Fig. 11 is a fragmentary view of the forward part of the completed upper prior to lasting, showing the stitched seams which unite the several parts;

Fig. 12 is a view generally similar to Fig. 4, but illustrating a modified form of guard roll;

Fig. 13 is a perspective view of a suitable core member or pad for the roll of Fig. 12;

Fig. 14 is a fragmentary section, generally similar to Fig. 12, illustrating another form of guard roll;

Fig. 15 is a perspective view of the core member employed in the roll shown in Fig. 14; and

Fig. 16 is a plan view of a core member of slightly different shape than that shown in Fig. 10 and which may be preferred under some circumstances.

Referring to the drawings the numeral 1 designates a pump of substantially usual type except for the inclusion of the present invention. This pump comprises the sole 2, the high heel 3 and the vamp 4, the latter having an upper edge which forms the foot-receiving opening 5, the throat end of the foot-receiving opening being defined by the cushion-like guard-roll 6 constituting the present improvement.

The upper of the pump chosen for illustration by way of example, comprises a whole vamp 4^a (Fig. 6) having the forepart portion 7 and the quarter portions 7^a and 7^b whose inner edges 8 and 9 border the foot-receiving opening in the completed shoe. These edges 8 and 9 terminate forwardly at the points 11 and 12 respectively, between which the forepart portion 7 of the vamp is furnished with a projecting integral tab 10. An area of the vamp and tab material at opposite sides of the imaginary line joining the points 11 and 12 is furnished with a multitude of small perforations 13, such perforations here being shown as disposed in rows defining a lenticular area. While it is preferred to provide the perforations at both sides of a line joining the points 11 and 12, it is contemplated that under some circumstances the perforations may be omitted at one or the other side of this line.

The upper as here illustrated by way of example also comprises the leather lining member 13^a and the fabric lining member 14. The member 13^a has the forward edges 15 and 16 and the member 14 has the rearward edges 15^a and 16^a, the edges 15 and 16 overlapping the edges 15^a and 16^a when the lining members are properly assembled and united.

The upper, as here illustrated, also comprises the doubler member 17 (Fig. 9) having the forepart portion 7^a which substantially conforms to the forepart portion of the lining member 14 and also having the foot-receiving opening 18 provided with the throat edge 19, it being noted that the opening 18 extends further forward than the foot-receiving opening in the vamp.

In accordance with the present invention, and as illustrated in Fig. 10, a cushioning core 20 is provided for the purpose of plumping and rounding the guard-roll which, in accordance with the present invention, defines the throat end of the foot-receiving opening. This core is cord-like in character to the extent that it is elongate, transversely flexible, resistant to stretch, much more nearly approximating the cylindrical than the sheet form, and in most embodiments is substantially uniform in cross sectional size and contour from end to end. As shown in Figs. 4, 5 and 10, this core 20 comprises a stuffer 21 which may, for example, be a more or less cylindrical length of cotton batting or other inherently springy cushion-like material, and a casing 22, for example, a piece of sheet material such as firm cloth or soft leather folded

about the stuffer 21, and if desired having its edges stitched together as indicated at 22^a. This casing 22 is of a material which has little stretch as compared for example with rubber or fabric containing rubber thread, so that the completed core is substantially inextensible in the direction of its length. This core is disposed against the inner side of the vamp 7, as shown in Fig. 10, before the lining is assembled with the vamp, and is of such a length as to extend laterally out beyond the points 11 and 12. If desired, this core may be temporarily secured in this position, prior to its permanent union to the other parts of the upper, by means of adhesive or the like, although this may not be necessary. After this core has been disposed as shown in Fig. 10, the tab 10 of the vamp is curled inwardly so as to form a tubular bight and to embrace the core within said bight as shown in Fig. 4. As thus arranged, the perforated portion of the vamp material embraces the core and forms the covering of the guard roll while the unperforated free end portion of the tab 10 extends beneath the forepart of the vamp to a substantial distance forwardly of the throat opening and lies substantially parallel to the inner face of the vamp proper.

The lining members 13^a and 14, are assembled and joined by one or more stitched seams 23 (Fig. 11). The complete lining is disposed at 30 the inner side of the vamp with the edge 13^b just forward of the partly formed roll 6. The vamp 7, the forwardly projecting portion of the tab 10, and the lining member 13 are then permanently united by the stitched seam 24. This 35 seam may extend around the entire top of the pump and may be that which is used in forming a French cord or other edge finish at the top of the pump, and extends transversely across the ends of the core 20 so as to anchor the latter 40 securely to the vamp—it being noted that the forward bight of the seam is spaced forwardly from the throat end of the foot-receiving opening, said throat end of the opening being defined by the rear contour of the roll 6.

The doubler 17, if not earlier assembled with the vamp, may now be introduced between the vamp and the forward part of the lining, being adhesively or otherwise secured to the vamp, it being noted that, by reason of the deep throat 18 of this doubler, the tab 10 may be extended forwardly to a substantial distance from the throat end of the foot-receiving opening of the vamp without unduly increasing the thickness of the upper material at this point but at the same time providing two thicknesses of the vamp material outside of the line of union of the two lining members, thereby effectively concealing the location of this line of union of the lining members at the exterior of the vamp.

The seam 24, which firmly joins the tab 10 to the main body of the vamp 7, so draws and constricts the covering and core as to plump or distend the covering of the roll 6, so that in the finished upper this roll is generally elliptical or 65 even nearly circular in transverse section thus providing a very broad, distinctly rounded, soft and comfortable cushion for engagement by the wearer's foot. Moreover, since the material forming the core of the roll is substantially inextensible transversely of the shoe, there is no danger that the upper will stretch, even after a considerable period of wear, and thus the original fit and good looks are preserved. The perforations 13 in the outer or covering member of 70

the roll furnish ample ventilation so that moisture absorbed from the foot into the soft absorbent core portion of the roll is readily dissipated and thus the outer covering of the roll does not rapidly deteriorate from the effects of absorbed perspiration as might well be the case if so thick and plump a roll were used without provision for ventilation.

By proceeding as above described, the outer covering of the roll has the same surface finish as the adjacent portions of the upper, and as specifically illustrated consists of an integral portion of the vamp material. The perforations 13, even though ample to provide for proper ventilation, need not be so large as seriously to detract from the appearance of the shoe, and in fact may be so disposed as to afford a distinctly ornamental effect. On the other hand, these perforations do not substantially weaken the vamp material constituting the cover for the roll, so that this material does not easily stretch and thus get out of shape.

While the core 20 illustrated in Figs. 4, 5 and 10, is a desirable construction, it is contemplated that cores of other type may be employed, one such arrangement being shown in Figs. 12 and 13. In this modified form, the core member 25 consists merely of a cord-like but substantially non-stretchable length of material, for example a soft rope comprising strands of soft cotton or paper twine, or a cylindrical length of other soft springy material, for example wood-pulp, regenerated cellulose, or the like, this core being disposed against the inside of the vamp in the same way as the core 20 of Fig. 10, and embraced in the fold of the vamp material so that the perforated portion of the vamp material encircles the core 25, it being understood that the ends of the core will be anchored firmly to the vamp by the seam 24 in the same way as already described with reference to the core 20.

A further form of core is shown in Figs. 14 and 15, wherein the core consists of two or more plies of resilient sheet material of appropriate type, preferably substantially inextensible, and which, for example, may be a fabric made from cotton or other fibers. Material of this type is commonly used in shoes as linings or doublers and when employed as a core, in accordance with the present invention, is arranged in the same way as the core 20 of Fig. 10, and embraced by the perforated part of the vamp and secured permanently in place in the same way as the pad 20. A soft resilient core material is desirable as affording the requisite cushion-like effect.

In Fig. 16 a core of somewhat different external shape is illustrated comprising a central portion 27 and end portions 28 which are of less cross-sectional dimensions than the central portion, the central portion being that which is embraced by the perforated upper material and the end portions forming the anchoring parts and by reason of their lesser bulk helping to avoid the formation of any undesirable lumps in the vamp adjacent to the forward corners of the throat.

While certain desirable embodiments of the invention have herein been described and illustrated by way of example, it is to be understood that the invention is not necessarily limited to these precise embodiments but is to be regarded as broadly inclusive of any and all modifications falling within the scope of the appended claims.

I claim:

75 1. A pump comprising an upper having a foot-

receiving opening, the upper including a vamp and a lining, the vamp having an integral tab which is curled inwardly to form a tubular bight with the free extremity of the tab in contact with the inner face of the vamp proper, said 5 bight constituting the covering of a plump, cushion-like, guard roll having an internal core and defining the throat end of the foot-receiving opening of the upper, the longitudinal axis of the roll lying substantially in the upward extension of that geometrical surface which is defined by the contacting faces of the vamp and the tab, the core of the roll being flexible, elongate and substantially inextensible transversely of the pump and of such cross-sectional size and shape 10 as to keep the tubular bight of the tab distended out of the extended surfaces of the outer face of the upper and the lining contacting face of the tab, said core member being disposed wholly rearward of the throat end of the foot-receiving opening of the lining, and means permanently securing the opposite ends respectively of the core member to the material of the vamp.

2. A pump comprising an upper provided with 25 a foot-receiving opening, the upper including a vamp and a lining, each of said parts of the upper having a foot-receiving opening, the vamp having an integral tab which is curled inwardly about and snugly embraces a flexible elongate core member of such transverse sectional shape and size as to distend the encircling material of the pad so as to aid in forming a plump guard roll peripherally curved in transverse section and which defines the throat end of the foot-receiving opening of the upper, the core member comprising a stuffer member and a casing enveloping the stuffer member, the casing being substantially inextensible transversely of the pump and being located wholly to the rear of the throat end of the foot-receiving opening of the lining, the free end of the tab being disposed substantially parallel and adjacent to the inner face of the vamp proper, and switches permanently uniting the ends of the core member to the vamp.

3. A pump comprising an upper having a foot-receiving opening, the upper including a vamp and a lining, the vamp having a tab at the throat end of the foot-receiving opening, said tab being curled inwardly to form a tubular bight with the free extremity of the tab interposed between the lining and the inner surface of the vamp proper, said bight constituting the exposed or outer element of a plump, cushion-like guard roll which defines the throat end of the foot-receiving opening of the completed pump, said roll being substantially inextensible transversely of the pump, the longitudinal axis of the roll lying substantially in the upper extension of that geometrical surface which is defined by the inner face of that part of the vamp which overlies the tab, the material of the vamp which constitutes said exposed or outer element of the guard roll being provided with a multitude of small perforations whereby its softness and flexibility is enhanced, and stitches permanently uniting the vamp, tab and lining, said stitches being disposed forwardly of the transversely extending axis of the guard roll.

4. A pump comprising an upper having a foot-receiving opening, the upper including a vamp and a lining, the vamp having a tab at the throat end of the foot-receiving opening, said tab being curled inwardly to form a tubular bight with the free extremity of the tab interposed between 70 75

the lining and the inner surface of the vamp proper, said bight constituting the exposed or outer element of a plump, cushion-like guard roll which defines the throat end of the foot-receiving opening of the completed pump, and which is substantially inextensible transversely of the pump, the longitudinal axis of the roll lying substantially in the upper extension of that geometrical surface which is defined by the inner face 5 of that part of the vamp which overlies the tab, the material of the vamp, in the vicinity of the junction of the tab and vamp proper, having therein a multitude of small perforations whereby to make it soft and flexible, the perforated area being substantially symmetrical with its axis of symmetry substantially coincident with the throat end of the foot-receiving opening of the vamp.

5. A pump comprising an upper having a foot-receiving opening, the upper including a vamp and a lining, the vamp having a tab at the throat end of the foot-receiving opening, said tab being curled inwardly to form a tubular bight with the

free extremity of the tab interposed between the lining and the inner surface of the vamp proper, said bight constituting the exposed or outer element of a plump, cushion-like guard roll which defines the throat end of the foot-receiving opening of the completed pump, the longitudinal axis of the roll lying substantially in the upper extension of that geometrical surface which is defined by the inner face of that part of the vamp which overlies the tab, the material of the vamp 10 having a perforated area of substantially lenticular contour at the junction of the tab with the vamp proper, the longitudinal axis of the perforated lenticular area being substantially coincident with the throat end of the foot-receiving 15 opening of the vamp and the perforated material forming the wall of said tubular bight, the guard roll having therein cushioning material which assists in imparting to the roll a distinctly rounded peripheral contour in transverse section.
